CLAIM

The ornamental design for an anti-vandal door pull, as shown and described.

DESCRIPTION

FIG. 1 is a front and top perspective view of an anti-vandal door pull, showing our new design;

FIG. 2 is a rear elevation view thereof;

FIG. 3 is a top plan view thereof, the bottom plan view being a mirror image;

FIG. 4 is a front elevation view thereof;

FIG. 5 is a left side elevation view thereof; and,

FIG. 6 is a right side elevation view thereof.
